SAFETY PLATE FOR GAS BURNERS

Emanuel J. Sonn, Brooklyn, N. Y.

Application June 19, 1934, Serial No. 731,363

1 Claim. (Cl. 158—113)

This invention relates to cooking ranges and more particularly to the gas burning unit thereof.

In the types of burners heretofore used a constant danger is incurred by the boiling over of 5 cooking vessels by which the liquid thus emitted extinguishes the burner flame.

It is the primary object of my invention to provide a simple and economical device which may be conveniently attached to a burner and which 10 will inevitably forestall any occurrence of the above mentioned hazard.

It is a further object of my invention to provide a plate readily detachable from the burner for cleaning by which the jets of the burner are 15 protected from extinguishment occurring by the boiling over of a cooking vessel.

The invention will be fully and comprehensively understood from a consideration of the following detailed description when read in connection with 20 the accompanying drawing which forms part of the application, with the understanding, however, that the improvement is capable of extended application and is not confined to the exact showing of the drawing nor to the precise construction 25 described and, therefore, such changes and modifications may be made therein as do not affect the spirit of the invention nor exceed the scope thereof as expressed in the appended claim.

In the drawing:

30 Fig. 1 is a plan view of the usual form of burner with the safety plate of my invention affixed thereto.

Fig. 2 is a side elevational view of Fig. 1 and showing the range grate.

35 Fig. 3 is a sectional view on line 3—3 of Fig. 1; and

Fig. 4 is an end elevational view on line 4—4 of Fig. 1.

40 Referring to the drawing for a more detailed description thereof, numeral 5 indicates the usual form of burner unit comprising a series of branch burners supplied with the fuel gas mixture thru a manifold 6 and the fuel mixer 7.

My device comprises a substantially flat plate 8 composed of a series of strips 9 arranged to conform to the outline of the burner, covering an adequate margin thereof. The safety plate 8 is supported horizontally in spaced relation to the burner by the brackets 10 or other suitable form of support. Brackets 10, being attached to the bottom of the plate, are provided in sufficient number to suitably support the safety plate 8 and comprise a pair of diverging prongs 10 5 11 which straddle the respective branches of the burner. The strips 9 are of a minimum width but sufficient to shed any liquid falling on same.

Altho my safety plate will operate on the burners of the usual type wherein the jets thereof issue a substantially vertical flame, I have provided an arrangement of these jets whereby the use of my device will not reduce the efficiency of the burner but will however afford adequate protection for same. This arrangement is illustrated 20 clearly in Fig. 3 and comprises the arrangement of the jets of the burner in rows, the jets being at angles to each other to issue diverging flames which will impinge upon the longitudinal edges 25 of the safety plate and which will project beyond same to contact with the bottom of the cooking vessel.

What is claimed as new is:

The combination with a gas burner having a plurality of radially arranged arms and each 30 arm having a series of gas outlets, of a safety plate comprising a plurality of arms respectively disposed directly over and spaced from the gas outlets, bifurcated supports extending downwardly from certain of said plate arms and 35 straddling corresponding arms of the burner, said outlets being obliquely directed outwardly relative to the sides of the arms of the safety plate so that the flames will pass the sides of the arms of the plate. 40

EMANUEL J. SONN.
